METHOD AND APPARATUS FOR SWAGING INTERNAL THREADS

Arthur J. Richards, Detroit, Mich.

Application February 16, 1953, Serial No. 336,988

6 Claims. (Cl. 10—86)

The present invention relates to a screw threaded fastening device, and has for an object to provide a fastening device having a screw thread formed in a metal blank by a pressing operation with a shaped punch.

It is a further object of the present invention to provide a fastening device having a screw thread formed in the aperture of a metal blank by metal displaced from adjacent its end.

It is still a further object of the present invention to provide a fastening device that can be fabricated in a continuous operation from a strip of metal.

It is another object of the present invention to provide a fastening device that is economical to manufacture and can be made in various shapes in the pressing operation.

Other objects and features of the invention will become apparent as the description proceeds especially when taken in conjunction with the accompanying drawings wherein:

Figure 1 is a view of one face of the device.

Figure 2 is a sectional view taken through line 2—2, Fig. 1.

Figure 3 is a view of the opposite face of the device shown in Fig. 1.

Figure 4 is a sectional view taken through line 4—4, Fig. 3.

Figure 5 is a sectional view of the blank before the thread is pressed in place.

Figure 6 is a side elevation of the punch used to press the thread in the blank.

Figure 7 is a plan view of the punch looking in the direction of the arrows 7—7 in Fig. 6.

Figure 8 is a side elevation partly in section showing the blank on the locating pin and the punch in position after pressing in a thread.

Figure 9 is a side elevation of the pin used for locating the blank after the portion of the thread has been pressed in from one side.

Fig. 10 is a plan view looking in the direction of the arrows 10—10, Fig. 9.

Figure 11 is a side elevation partly in section showing the blank on the locating pin and the punch in position after pressing in a portion of the thread from the face opposite to that in which a thread has already been pressed.

Figure 12 shows a modified form of the invention partly in section.

Referring to the drawings the blank 10 preferably of soft steel has an aperture 11 extending therethrough. The aperture is round and can be punched out of the metal by means of a punch and die. The diameter of the aperture is determined from the size of the thread to be pressed and is approximately equal at the major diameter of the thread formed.

A locating pin 12 is positioned in a die block 14 and has a projecting portion 15 of a diameter to snugly fit into the aperture of the blank. The blank 10 is placed on the pin 12 and rests on the surface 16 that extends around the periphery of the pin. The punch 20 is positioned in a die block 22 so that its axis is directly in line

2

with the axis of the pin 12. It will be understood that the die blocks indicated at 14 and 22 can be used with any conventional die sets or type of apparatus suitable for the purpose of performing a pressing operation.

5 The punch 20 is made from a tool steel that can be suitably hardened and has a spiral shaped surface 30 that is axially and radially perpendicular to the axis of the punch. The radius of the inner edge 32 of the surface 30 is concentric with the axis of the punch and is 10 equal to one half of the major diameter of the thread formed by the punch. The edge 32 has a helix angle approximately equal to the helix angle, when taken on the major diameter, of the thread formed by the punch. The thread shaping surface 34 extends from edge 32 15 towards the axis of the punch at an angle of 30 degrees with the surface 30. The inner edge 35 of the surface 34 has a radius equal to one half of the minor diameter of the thread formed by the punch and has a helix angle approximately equal to the helix angle, when taken 20 on the minor diameter, of the thread formed by the punch. The metal deforming surface 36 is substantially axially and radially perpendicular to the axis of the punch. The outer edge 38 of the surface 30 is eccentric with the axis of the punch beginning at point 40 having the smallest 25 radius and gradually increasing in radius to the point 41. The edge 38 is sharp, enabling it to shear the metal of the blank. The edge 42 has the same radius as the radius of the aperture 11 of the blank.

As the punch is moved toward the blank the point 40 30 makes initial contact and as the punch is forced into the blank the edge 38 shears the metal progressively along its length forcing the metal inwardly against the surface 34 and downwardly into the aperture to form a portion of the thread. The point 40 moves further downward 35 into the metal than the point 41 and therefore less radial thickness of metal off of the wall of the aperture is required to be forced inwardly and downwardly at the point 40 than is required at point 41 to form a thread of equal fullness around the periphery of the aperture. 40 The punch is forced into the metal until the point 44 is into the aperture a distance of one half of the thickness of the blank. The area of the surface 30 determines the amount of metal forced into the aperture to form the thread. This area is developed according to the size 45 and pitch of the thread to be formed and the thickness of the blank to be used and is of a size to provide a thread of equal fullness around the periphery of the aperture. A blank of sufficient thickness is used so that the punch will penetrate far enough into the metal to 50 allow the edge 38 to form a shoulder 45 in the blank for purposes later to be described. When the proper amount of metal has been displaced it has been found that the side 46 of the thread will assume a form that 55 will give a symmetrical thread having approximately a 60 degree angle. After forming this portion of the thread the punch is withdrawn from the blank.

The amount of metal displaced by the punch also varies 60 with the angle the spiral surface makes with the axis of the punch. Figure 12 shows a modification of the invention in which the punch 47 is the same as punch 20 previously described with the exception that the spiral surface 48 instead of being axially and radially perpendicular or 90 degrees with the axis of the punch is axially and radially angular or less than 90 degrees with the 65 axis of the punch. By varying this angle the fullness of the thread formed will vary.

Figure 12 also shows a modification of the locating pin used in forming the thread. The pin 49 is similar to pin 12 previously described and has an upstanding portion 50 of a diameter to fit snugly into the aperture 11 of the blank. The surface 51 is made to conform to the underside of the thread that is to be formed by the punch used

with the pin. Either the punch 20 or the modified punch 47 can be used with the pin. The punch is pressed into the blank forcing the metal downwardly and inwardly against the surface 51. The portion 50 is made of a length to project into the aperture a distance required to position the thread where desired in the aperture and where a full thread will be obtained when the punch is stopped just short of contact with the pin. A thread of exact desired fullness will be obtained. If less than a full thread is desired the punch is stopped after moving a less distance than required for a full thread.

In the next operation the thread is formed from the opposite face of the blank. A locating pin 52 has an upstanding portion 53 shaped to the contour of the impression made by the punch 20. The edge portion 54 has the same contour as the edge 38 and the edge portion 56 has the same radius as the edge 42 of the punch 20. The point 58 corresponds to the point 40 of the punch. The locating pin 52 is positioned in a die block indicated at 60. The blank having a portion of thread formed from one face is located on the pin 52 with the portion 53 fitting into the impression 62 formed by the punch with the shoulder 45 acting to locate the blank. The punch 64 is the same as the punch 20 previously described and is positioned in a die block indicated at 66 with the axis of the punch in alignment with the axis of the pin. The punch 64 is positioned radially in relation to the pin 52 so that point 68 corresponding to point 40 of the punch is in line with point 58 of the pin. The punch is forced into the metal until the point 70 that corresponds to point 44 of the punch 20 is into the aperture a distance of one half of the thickness of the blank where the portion of the thread being formed is in alignment with the portion of the thread formed from the opposite face. The punch is withdrawn and the blank removed from the pin.

While the foregoing operation has been described as designed to form a portion of a thread from one side of the blank at a time, it will of course be understood that the thread can be formed from both sides at the same time by providing a punch at each side of the die set and locating the blank by means other than the aperture.

The apparatus for carrying out the invention has been disclosed in the foregoing manner for purposes of clarification. It will be appreciated that other types of pressing apparatus can be used to carry out the pressing operation. If desired, a progressive type die whereby a strip of metal stock can be fed into one side and the operation performed continuously in succeeding stations of the die, can be used. It will also be appreciated that a device having other shapes and forms can be produced in suitable dies in the pressing operation. For instance the blank can be made round or irregular in shape or if desired projections can be pressed from one face of the blank and the device used as a welding type nut.

Such modifications of my invention may be employed as lie within the scope of the appended claims without departing from the spirit and intention of the invention.

What I claim as my invention is:

1. The method of forming a screw thread in a metal blank with a punch having an end portion provided with a surface shaped to correspond to one side of the thread to be formed, comprising providing a metal blank having an aperture therein of a diameter approximately equal to the major diameter of the thread to be formed, applying pressure with the punch against the metal adjacent one end of the aperture beginning at the point of initial contact of the punch with the metal and continuing progressively around the aperture with the outer periphery of contact of the punch with the metal increasing in radius in respect to the axis of the aperture as the punch is forced inwardly thus forcing a flow of metal axially and radially inwardly of the aperture against the thread shaping surface of the punch.

2. The method of forming a screw thread in a metal blank with a punch having an end portion provided with

a surface shaped to correspond to one side of the thread to be formed, comprising providing a metal blank with an aperture therein having a diameter approximately equal to the major diameter of the thread to be formed, applying pressure with the punch against the metal adjacent one end of the aperture beginning at the point of initial contact of the punch with the metal of the blank and continuing progressively around the aperture with the outer periphery of contact of the punch with the blank increasing in radius in respect to the axis of the aperture as the punch is forced inwardly, forcing a flow of metal axially and radially inwardly of the aperture against the thread shaping surface at the end of the punch, thereafter applying pressure with the punch against the metal adjacent the opposite end of the aperture beginning at the initial contact of the punch with the metal at a point properly phased circumferentially with respect to the thread formed by the preceding step, and continuing progressively around the aperture with the outer periphery of contact of the punch with the blank increasing in radius with respect to the axis of the aperture as the punch is forced inwardly, thus forcing a flow of metal axially and radially inwardly of the aperture against the thread shaping surface at the end of the punch.

25. 3. The method of claim 2 in which the thread formed from one side of the aperture joins with the thread formed from the opposite end of the aperture to form a substantially continuous thread.

4. The method of forming a screw thread in a metal blank with a punch having an end portion provided with a thread shaping surface formed to correspond to one side of the thread to be formed in the blank, comprising providing a blank having an aperture whose diameter is approximately equal to the major diameter of the thread to be formed, applying pressure with the punch against the metal adjacent an end of the aperture beginning at the point of initial contact of the punch with the blank and continuing progressively around the aperture with the outer periphery of contact of the punch with the blank increasing in radius in respect to the axis of the aperture as the punch is forced inwardly of the aperture, thus forcing a flow of metal axially and radially inwardly of the aperture against the thread shaping surface at the end of the punch and against a thread shaping surface at the end of a locating pin received in the aperture.

5. A punch for forming a thread within a cylindrical opening in a blank, the opening having a diameter approximately equal to the root diameter of the thread to be formed, said punch having a helically disposed thread shaping surface of less than 360 degrees angular extent and conforming to a desired thread form, a metal deforming surface located to extend generally radially outwardly from the outer edge of said thread shaping surface, and a generally cylindrical surface intersecting said metal deforming surface at its radially outer edge and forming a curved shearing edge therewith, the radial dimension of said metal deforming surface being progressively larger from the end thereof positioned to make initial contact with said blank to the other end to provide uniform thread fullness in the blank.

6. Apparatus for forming a thread within a cylindrical opening in a blank, the opening having a diameter approximately equal to the root diameter of the thread to be formed, comprising a support having a locating pin shaped to fit within the opening in the blank and terminating within the opening in a helical thread shaping end surface of less than 360 degrees angular extent conforming to the desired thread form, a die having a helically disposed thread shaping surface of less than 360 degrees angular extent and conforming to a desired thread form, a metal deforming surface located to extend generally radially outwardly from the outer edge of said thread shaping surface, and a generally cylindrical surface intersecting said metal deforming surface at its radially outer

edge and forming a curved shearing edge therewith, the radial dimension of said metal deforming surface being progressively larger from the end thereof positioned to make initial contact with said blank to the other end to provide uniform thread fullness in the blank, the thread shaping surfaces of said die and pin being movable to shape the metal sheared from said blank and displaced by the metal deforming surface into desired form therebetween.
